PARTITION

Axel G. Dawson, Jamestown, N. Y., assignor to
Dahlstrom Metallic Door Company, Jame-
town, N. Y., a corporation of New York

Application May 4, 1932, Serial No. 609,135

4 Claims. (Cl. 189—34)

This invention relates to an improvement in partitions, the preferred embodiment of which discloses means for connecting and locking together adjacent panel units. 5
The principal object of the invention lies in the provision of means for removably and spacedly locking adjacent panel elements of a partition. Another object of the invention lies in the provision of panel locking means adapted to receive 10 face plates by which to simulate the appearance of the usual type post or pilaster.

A further object of the invention lies in the provision of means for joining an angularly disposed partition section to a straight wall unit. 15
Other and further objects of the invention may be more clearly understood from a consideration of the following specification which is taken in conjunction with the accompanying drawing, and in which

Fig. 1 is a fragmentary front elevation of a partition embodying one form of this invention; Fig. 2 is an enlarged horizontal sectional view taken substantially on the line 2—2 of Figure 1; Fig. 3 is a fragmentary perspective view, showing 25 the intermediate locking connection for adjacent panel units;

Fig. 4 is a perspective view of one of the locking elements;

Fig. 5 is a horizontal sectional view, showing 30 the means of connecting an angular panel unit to a straight line partition section; and

Fig. 6 is a perspective view of the structure shown in Figure 5.

Referring to the drawing, the invention is 35 shown mounted in a partition section, generally indicated by the reference numeral 10. This partition comprises adjacent panel units 11 and 12. Intermediate these units a pilaster face plate 13 is located. Adjacent panel units are identical 40 and consequently but one of them will be described in detail. Each of these units includes a panel supporting frame 14 having vertical rails 15. Perpendicular side walls 16 converge to form an inwardly opening channel 17 in which a glass 45 or other panel 18 is located. The walls 16 are terminated by a longitudinally extending outwardly opening recess 20 formed by flanges 21, 22, 23 and 24. The flange 21 restricts the size of the mouth of the recess 20. At certain predetermined intervals the flange 21 is cut away a few inches for a purpose about to be described. 50

It is contemplated to eliminate the customary practise of locating a plurality of posts or pilasters throughout the partition and supporting the 55 panel units thereby. However, since a break in

the straight line of the partition has been customary in design and because such breaks permit erection of intermediate angularly disposed partition sections, it is contemplated to simulate the provision of posts or pilasters between adjacent panel units. This is accomplished through the use of partition height face plates 13. The novelty of such an arrangement lies in the substitution of suitable structure for spacedly tying together adjacent panel units and providing in 5 the tying means further means for engagement with the face plate 13. This is accomplished through the provision of clips 26 which are each formed with an outer straight wall 27 which terminates in longitudinal ribs or shoulders 28. 10 From the shoulders 28, flanges 30 project, being substantially at right angles to the wall 27. The flanges 30, at their upper end, terminate in small right angle flanges 31 which are tapered toward the lower end of the clip to form wedge-like portions 32. With the exception of slots 33, cut into the flanges 21, the recess 20 has a full length restricted opening. The slots 33 have a slightly greater length than that of the clips 26. The clips 26 may therefore be inserted into the adjacent slots 33 of adjacent panel units and be moved downwardly to occupy a position such that the clip flanges 31 will interlock with the flanges 21. Since it is possible that the panel units may not be exactly aligned for the ready insertion of 20 clips 26, the wedge-shaped surfaces 32 of the flanges 30 tend to laterally move one or both of the adjacent panel units to the proper position. The number of slots 33 and clips 26 will be dependent largely on the weight and size of the 35 panel units these clips are to secure. When a sufficient number of clips have been inserted into the recesses 20 of the adjacent walls of adjacent panel units, the same procedure is resorted to to tie the opposite adjacent panel walls. It will be 40 noted that access to the space 35 within the partition may readily be had for the purpose of installing wiring conduits, etc. The face plate 13 is arranged with inwardly directed flanges 36. Since these flanges are more or less spring-like, 45 they are adapted to snap over the shoulders 28 of the clips 26 and abut the wall 16 of the panel units. It will readily be understood that, when adjacent panel units are thus connected, the partition presents the appearance of comprising a 50 number of panel units supported by intermediate posts or pilasters. It will also be understood that access may readily be had to wiring systems located in the partition by removing one or both of the face plates 13.

Attention is now particularly directed to Figures 5 and 6 of the drawing wherein is shown a method of joining an angularly disposed panel unit to a straight line partition. In this instance, it is necessary to removably secure three adjacent panel rails 15. The third panel unit 38 is so located that the flanges 22 of the rail 15 abut the adjacent flanges 21 of the rails of the adjacent panel units 11 and 12. The adjacent flanges 21 are provided with corresponding slots 33 and into each of these slots is inserted an angle clip 39, the walls 40 and 41 of which form spaced tapered legs 42 and 43. When the clip 39 is inserted into the adjacent openings 33 and moved downwardly, the legs 42 and 43 draw the adjacent panel units into close engagement with each other. The clip 39 performs the same function as the clip 26, being held in place by the spring-tension of the metal.

It will be noted that by reason of the structure above described, it is possible to reduce the cost of erecting many intermediate posts or pilasters without sacrificing the simplicity of design of a partition. It will also be noted that a partition of this type is extremely flexible in that sections may be added to or removed from or angularly directed units erected without disrupting that portion of the partition previously set up.

Although applicant has shown and described only one modification of this invention, it will be apparent to those skilled in the art that other modifications or adaptations may be made without departing from the spirit and scope of the invention as defined in the hereunto annexed claims.

Having thus set forth my invention what I

claim as new and for which I desire protection by Letters Patent is:

1. In a metal partition for buildings having adjacent panel units, means engageable with adjacent portions of said units for securing said units in fixed spaced relationship, wedge portions on said means for laterally adjusting said units, and a face plate enclosing the space between said units, said face plate being engaged with said means. 10

2. In a metal partition for buildings having adjacent panel units, rails forming the edges of said units, outwardly directed flanges on said rails, said flanges being cut to produce corresponding openings, a clip projectable into said openings said clip having wedge shaped portions engageable with said flanges, said portions serving to laterally adjust and secure said panel units. 15

3. In a metal partition for buildings having angularly arranged panel units, rails forming adjacent edges of said units, means engageable with said rails for securing said units in fixed abutting relationship, and wedge portions on said means for laterally adjusting said units to bring them 20 into abutment. 25

4. In a metal partition for buildings having angularly arranged panel units, rails forming adjacent edges of said units, flanges on said rails, said flanges being cut to produce corresponding transverse openings, means projectable into said openings to engage said flanges and secure said units in fixed relationship, and wedge portions on said means for laterally adjusting said units during assembly. 30 35
